UNITED STATES PATENT OFFICE.

EDWARD H. MARKLEY, OF PHILLIPSBURG, NEW JERSEY, ASSIGNOR TO INGERSOLL-RAND COMPANY, OF JERSEY CITY, NEW JERSEY, A CORPORATION OF NEW JERSEY.

TUBE-CLEANING APPARATUS.

Application filed August 6, 1926. Serial No. 127,615.

This invention relates to tube cleaning apparatus and more particularly to apparatus for cleaning foul steam condenser tubes.

It is an object of this invention to enable the tubes to be cleaned in a simplified manner. A further object of the invention is to dissolve the fouling material from the tubes and to scrub it loose simultaneously.

10 Other objects and advantages of the invention will be in part obvious and in part pointed out hereinafter.

Referring to the drawing,

Figure 1 is a longitudinal sectional view 15 of a tubular condenser and apparatus for cleaning the tube constructed in accordance with the practice of the invention, and

Figure 2 is an enlarged view in longitudinal section of a portion of the cleaning 20 apparatus.

Referring to the drawing, the cleaning apparatus comprises a tubular nozzle A provided with a plurality of perforations B and wound throughout its length with a 25 scrubber C, which may be in the form of a cord or rope having wire bristles projecting therefrom. The scrubber C lies in a helical groove C and may be rapidly and cheaply replaced when worn. The method of wrapping the rope about the nozzle A to form a helix causes the cleaning fluid to be whirled about the inside of the fouled tube and the fluid is thereby caused to come in contact with a large area of the tube wall and to 30 remain in contact with the wall for a longer period of time than is the case with the ordinary brush, thus permitting the fluid to be used to its fullest advantage in dissolving and removing the fouling from the tube wall.

40 By using rope brushes of varying diameter different sizes of tubes may be cleaned.

The nozzle A is preferably attached by threaded engagement as at D to a tubular shank E substantially the length of the tube 45 to be cleaned, the shank being preferably threaded as at F into a handle which comprises a rigid tube G surrounded by a tubular grip H preferably of asbestos or other suitable heat insulating material. The grip

50 H may be separated from the tube G by means of a coiled wire heat dissipator J. The forward end of the handle comprises a coupling K into which the shank E is adapted to be screwed as at F and threaded at L to receive the tube G. A flange O formed

integrally with the coupling K is adapted to hold the wire coils J and the grip portion H in position. At its rearward end the handle is provided with a sleeve P fitting over the tube G and rigidly attached thereto 60 and provided with a flange Q to prevent removal of the wire coils J and the grip portion H. The flow of fluid through the cleaning apparatus is controlled by a valve R which may be operated by means of a control lever S extending adjacent the grip portion H and adapted to be grasped by the operator holding the grip portion H. The handle S is preferably pivotally mounted on a pivot T supported by a projecting portion 70 U formed integrally with the sleeve P. A biasing spring V pressing against the lever S normally tends to close the valve R.

In the drawing the apparatus is shown 75 inserted in one of the tubes W of a tubular condenser. The cleaning solution is adapted to be supplied from a suitable tank X and pumped by means of a pump Y to a flexible hose Z. Ordinarily, the solvents for removing fouling matter from the tubes W is 80 heated as by means of steam supplied through a pipe b extending into the tank X.

In operation the pump Y is first started to supply the solvent through the hose Z to the cleaner. The nozzle A is then inserted into 85 the tube W by the operator grasping the handle at the grip portion H and the valve R is opened depressing the valve lever S. The operator then pulls the nozzle A back and forth in the tube causing the brush rope 90 C to scour the inner surface of the tube W. At the same time the solvent is supplied to the interior of the tube W through the tube G, the shank E and the holes B in the nozzle A to soften and wash away the particles 95 removed from the tube surface.

Great force may be required to push the nozzle A back and forth in the tube and in order to permit the apparatus to be operated by two men conveniently a hook or ring c 100 suitably mounted at the end of the nozzle A is provided by which the nozzle may be engaged to be pulled from the opposite end of the tube W.

Preferably the tubular shank E should be 105 as long as the tube W and to this end the shank E is made in a piece separate from the nozzle A and the handle so that for use of different length tubes W various lengths of shanks E may be utilized.

I claim:

A tube cleaning apparatus comprising a shank, a tubular perforated nozzle at one end of said shank having a helically grooved 10 external surface, and a brush wound around said nozzle in said groove, said brush comprising a rope having wire bristles projecting therefrom, said rope brush forming a helix about said tube and thereby causing cleansing fluid issuing from said perforations to follow a helical path about the interior of the tube being cleaned.

In testimony whereof I have signed this specification.

EDWARD H. MARKLEY.
